UNITED STATES PATENT OFFICE.

WILLIAM C. STEWART, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

PULLING-OVER MACHINE.

1,382,751.

Specification of Letters Patent. Patented June 28, 1921.

Application filed May 31, 1919. Serial No. 300,852.

To all whom it may concern:

Be it known that I, WILLIAM C. STEWART, a subject of the King of England, residing at Swampscott, in the county of Essex and 5 State of Massachusetts, have invented certain Improvements in Pulling-Over Machines, of which the following description, in connection with the accompanying drawings, is a specification, like reference characters on the drawings indicating like parts 10 in the several figures.

This invention relates to machines for use in the manufacture of boots and shoes for pulling uppers over lasts, and is herein illustrated in its application to a well known 15 type of pulling-over machine characteristic features of which are shown and described in United States Letters Patent No. 1,029,387 granted on June 11, 1912, upon an application 20 of R. F. McFeeley. It will be understood, however, that the invention is not limited in utility to the type of machine shown in said patent but is broadly applicable to various types of construction.

25 The invention provides important improvements in pulling-over machines in respect to provision of means for locating the tip line in the correct relation to the last and means for tensioning the upper properly 30 lengthwise of the last. In the machine herein shown the location of the tip line at the correct distance from the end of the last is insured and the upper is tensioned along the sides by a predetermined relative 35 movement of the upper and the last in a direction lengthwise of the last while the side grippers hold the margin of the upper. More particularly, the illustrative machine has means whereby the side grippers may be 40 closed initially upon the upper in a definite relation to the opposite ends of the tip seam and means for imparting to the toe gripper a rearward movement of predetermined extent while in contact with the toe end face 45 of the last to push the last rearwardly within the upper the required distance to give the proper length of tip. By this operation, moreover, the upper along the sides of the shoe is tensioned lengthwise from the heel 50 end forwardly, and the end portions of the tip seam are so positioned with reference to the subsequent forward pull on the middle portion of the seam by the toe gripper as to

prevent "bowing" of the tip line. Important features of the invention are to be 55 recognized in the novel organization whereby the desired results as to length of tip, straightness of the tip line, and lengthwise tensioning of the upper are secured.

A further feature of the invention consists in novel means for insuring the correct angular relation of the tip line to the longitudinal medial line of the shoe. To 60 this end the illustrative machine has means whereby the opposite side grippers may be 65 positioned in a predetermined relation lengthwise of the last, combined with heel rest positioning means designed to determine a corresponding definite lateral "swing" of 70 the heel part of the last. A further 75 advantageous characteristic of the novel construction shown resides in its adaptability to quick and accurate reversal in changing between right and left shoes.

The above and other features of the invention, including novel side gripper adjusting means, novel means for adjusting and controlling the toe gripper, novel means for adjusting the limit of lateral movement of the heel rest, and various details of construction and combinations of parts, will 80 now be described with reference to the accompanying drawings and pointed out in the claims.

In the drawings,

Figure 1 is a view in side elevation of 85 the head portion of a pulling-over machine in which the invention is embodied;

Fig. 2 is a perspective view of portions of the toe and side gripper controlling 90 means, parts being broken away to show the interior construction;

Fig. 3 is a view at a different angle of a portion of the toe gripper controlling means shown in Fig. 2;

Fig. 4 is a view in side elevation showing different positions of the toe gripper;

Fig. 5 is a perspective view of a portion of the mechanism shown in Fig. 1 for moving the toe gripper lengthwise of the last 100 and for controlling the grippers;

Fig. 6 is a view partly in side elevation and partly in section of mechanism for adjusting the toe gripper;

Fig. 7 shows the gripper spreading mechanism detached;

Fig. 8 is a plan view, with parts in section, of the side gripper adjusting means;

Fig. 9 is a developed cross section through a portion of the side gripper adjusting means 5 in the location indicated by the line 9—9 of Fig. 8;

Fig. 10 shows in perspective a portion of the adjusting mechanism seen at the right hand side of Fig. 8;

10 Fig. 11 is a perspective view of the heel rest and its adjusting means;

Fig. 12 is a view at a different angle, with a part shown in section, of the adjusting means shown in Fig. 11, and

15 Fig. 13 is a diagrammatic view illustrating the cycle of operations.

Machines of the general type illustrated comprise in their organization a gripper for engaging the upper at the toe end of the last 20 and grippers for engaging the upper at the opposite sides of the forepart. The side grippers in the construction herein shown comprise two pairs of upper gripping jaws 2 at each side, these jaws being mounted 25 and operated similarly to the construction shown and described in detail in United States Letters Patent No. 1,030,522, granted on June 25, 1912, on an application of R. F. McFeely, although it is to be understood 30 that the utility of the invention is not dependent upon the use of a duplex construction of this character. The gripper jaws at each side of the machine, as shown in said patent, are mounted on a gripper casing 4, comprising a separately movable part for each pair of jaws, and are first closed and then operated to pull the upper by lengthwise movement of a gripper bar 6 connected to an updraw lever 8 which is pivotally 40 mounted on the frame of the machine.

When the machine stands idle the gripper bar 6 and the casing sections 4 are relatively so disposed, in consequence of engagement of shoulders 10 on the casing sections with 45 portions 12 of the frame through which the gripper is guided, as to relieve the gripper jaws from the action of their closing springs (not shown). It will be understood that after the work has been properly positioned 50 the first portion of the movement of the bar 6 renders the springs effective to close the jaws upon the upper and that as the bar continues its movement the casing sections and the jaws are moved with it to pull the upper.

55 The gripper levers 8 are operated by means of a cam on a cam shaft 14 through a slide 16 which carries rods 18 encircled by springs 20 which bear upon the rear end portions of the gripper levers, the springs 60 being compressed as the slide is moved downward and the grippers thus operated to pull the upper yieldingly. The toe gripper comprises a pair of jaws 22 carried by a gripper casing 24, this gripper being operated through a bar 25 similarly to the side 65

grippers to close upon the upper and then to pull it by means of an updraw lever 26 yieldingly connected through a rod and a spring to a cam slide 28 operated by a cam on the cam shaft 14.

70 The machine is controlled by the usual starting treadle whereby upward movement is imparted to a treadle rod 30 against the tension of a spring 32, the upper end of this rod engaging a slide 34 whereby the clutch 75 (not shown) is actuated through a clutch rod 36 to cause movement to be imparted from the main driving shaft to the pulley 38 on the cam shaft 14. For a more complete understanding of the details of this 80 construction reference may be made to prior Patent No. 791,986, granted on June 6, 1905, on application of R. F. McFeely. Upon the first actuation of the clutch the toe and side grippers are operated as above described to 85 pull the upper, the last being held against the pull of the grippers by means of sole rest 40 against which the bottom of the sole or insole is positioned when the work is presented to the machine, this sole rest also 90 receiving a short downward rocking movement to depress the last within the upper, as usual in this type of machine. As the upper pulling operation is effected, a heel rest 42 having divergent portions constructed 95 partially to embrace the heel end of the shoe is moved up yieldingly into supporting and positioning engagement with the shoe. In machines of the illustrative type as heretofore constructed the parts come automatically to rest at the end of the upper pulling operation in order to permit inspection 100 of the work and any adjustment which is found to be desirable in order to position the upper correctly in relation to the last 105 or to increase or relax the tension on any portion of the upper. The machine herein shown likewise is designed to come to rest at this point in the cycle, although, as will be hereinafter explained, the construction 110 herein provided eliminates the necessity for such inspection and adjustment as have been necessary heretofore as far as concerns length of the tip and the angular relation 115 of the tip line to the last.

When the machine is again started side clamp arms 43 are moved laterally into supporting and holding engagement with the shoe and the margin of the upper is wiped inwardly at the toe end and at the opposite 120 sides of the last and secured in place by wiping and tacking mechanisms which are carried by a front tacker arm 44 and side tacker arms 46. The operative inward movement of the front and side tacker arms 125 is permitted through provision for inward movement of the toe and side grippers when released by their controlling means, the side grippers being moved inwardly to some extent by overdraw springs 48 (Fig. 2) which 130

engage a plate 50 that bears on the outer sides of the casing members 4, and the toe gripper by similar springs 52 (Fig. 1). A latch 54 on the toe gripper and latches 56 on the side grippers are engaged by the corresponding inwardly movable tacker arms 44 and 46 to cause the grippers finally to release the upper, the tacks being then driven and the parts of the machine 10 turned to starting position. Since the general organization of the machine, except as modified for the purposes of this invention as hereinafter explained, may be and is herein shown as conformable substantially to the disclosure of the prior McFeely patents above mentioned, any further description of the details of construction of such general features may be dispensed with and reference may be made to said prior patents for 20 any further desired information as to such details.

It is contemplated that for the purposes of this invention the lengthwise positions of the last and of the upper will be determined independently when the work is presented to the machine, and to this end the toe gripper is so disposed as to permit the toe end face of the last to be positioned in engagement with the rear toe gripper jaw 30 which is fixed to the gripper casing, and the front pair of side gripper jaws 2 at each side of the last is provided with a mark 58 to indicate the correct location of the tip seam or tip line. It will be understood, however, that the correct location of the opposite ends of the tip seam relatively to the side grippers may be otherwise indicated to the operator than by the use of such marks. As the last and the upper are thus positioned, the tip seam is located farther from the toe end face of the last than required for the size and style of shoe. It is further contemplated, in order to insure the proper location of the upper in the side grippers, that these grippers shall be closed upon the upper before the machine is started, such closing movement in the construction shown being effected manually by a movement of the treadle rod 30 before the clutch is tripped. By reference to Fig. 1 it will be seen that as the machine stands idle a space is provided between the rear ends of the side updraw levers 8 and the top of the cam slide 16, the rear ends of the levers being held up against their operating springs 20 by means of additional springs 60 connected at their lower ends to pins 62 which project laterally from the gripper levers and at their upper ends to studs 64 secured 60 at the opposite ends of a plate 66 which extends across the tops of the tension adjusting nuts 68 on the gripper operating rods 18. The pins 62 extend through slots in depending links 70 which are connected at 65 their lower ends to bell crank arms 72, these arms having rigid connection with a forwardly extending arm 74 connected by a rod 76 to a clamp 78 on the treadle rod 30. Between the upper end of the rod 30 and the clutch tripping slide 34 a space is provided to permit a substantial extent of upward movement of the rod before the clutch is tripped. By such initial movement of the rod 30 the links 70 are operated through the rod 76 and the bell crank arms 74 and 72 to pull the rear ends of the side updraw levers 8 downwardly and thus to operate the gripper bars 6 in such manner as to permit the gripper jaws to be closed upon the upper by their closing springs. Correct location of the upper in the jaws is thus insured, and by further movement of the rod 30, which may or may not be continuous with its initial movement, the clutch is tripped and the machine is started.

The first movement imparted to the toe gripper upon the starting of the machine is a rearward swinging movement to cause it by engagement with the end face of the last to push the last backwardly a predetermined distance relatively to the upper held by the side grippers. For this purpose the machine is provided with a cam 80 fast on a cam shaft 82 which carries a pinion 84 engaged and driven by a pinion 86 on a shaft 88 which is conveniently formed as an extension of a shaft provided in machines of this type as a support for speed reducing gearing 90 (Fig. 1) between the pulley 38 and the main cam shaft 14, the pinions 84 and 86 being so proportioned that the cam 82 is rotated at the same rate as the main cam shaft 14. Engaging the face of the cam 80 is a roll 92 carried by a pivoted lever 94 which is connected at its upper end by means of a link 96 to a crank arm 98 on a rock shaft 100 mounted in bearings in a bracket 102 secured on the front of the frame of the machine. Fast on the shaft 100 is a crank arm 104 upon the outer end of which is pivotally mounted a frame member comprising two arms 106 one of which is provided with a slot 108 to receive a guiding pin 110 on the frame of the machine. The arms 106 extend rearwardly toward the toe gripper and are provided at their rear ends with plugs 112 which have slots in their inner ends to receive the opposite edges of a plate 114 secured on the front of the gripper casing 24. As the machine stands idle the opposite side edges of the plate 114 are within the slots in the plugs, as shown in Fig. 2, and the position of the gripper lengthwise of the last is thus determined. A spring 116 connected to the upper end of the lever 94 tends to swing the lever in a direction to hold its roll 92 in engagement with the cam and thus maintains the toe gripper yieldingly in its initial position. When the machine is started a rise α on the cam 80 en-

gages the roll 92 and operates the lever 94 and the connected parts to move the arms 106 rearwardly and thus to cause the toe gripper to push the last backwardly in the 5 upper to tension the upper along the sides and to locate the end face of the last at the correct distance from the ends of the tip seam held by the front pairs of side gripper jaws. The initial position of the toe gripper 10 and the limit of its rearward movement in engagement with the last are determined by an adjustable connection between the rock shaft 100 and the arm 98, comprising a worm 118 journaled in a bracket 120 fast on the 15 rock shaft and engaging the teeth of a gear segment 122 which is integral with the arm 98. By turning the worm 118 the rock shaft 100 may thus be rotated relatively to the gear segment 122 and the toe gripper moved 20 forwardly or backwardly through its connections to the crank arm 104. Turning of the worm may be effected by means of a knurled wheel 124.

In order to determine the proper adjustment of the toe gripper to give the correct length of tip through the automatic operation above described, consideration must be given both to the standard length of tip for the particular style of shoe upon which 25 the machine is to operate and to the size of the shoe, since the length of the tip not only varies with the size but may vary also in different styles of the same size. The machine is further provided with means for determining the correct adjustment of the worm 30 118 with regard to both these variables. By reference to Fig. 2 it will be seen that the wheel 124 carries on its front face a series of numerals any one of which may be presented 35 in view through a hole 126 in an adjustable segmental plate 128 which is fast on a spindle 130 (Fig. 6) extending centrally through the worm 118 and provided at its rear end with a spring 132 which tends to 40 hold the plate against the face of the wheel with a pin 134 on the plate in engagement in one of a series of holes in the face of the wheel, there being one hole for each of the numerals. A knob 136 projecting from the 45 plate 128 permits the plate to be pulled outwardly from the wheel 124 against the tension of the spring 132 and turned to bring the hole 126 over any one of the series of numerals on the wheel. These numerals, which 50 may or may not be arbitrary symbols, indicate different standard lengths of tip corresponding to different styles of shoes. The plate 128 carries on its marginal edge a plurality of marks 138 which indicate shoe 55 sizes, these marks being located opposite to numerals corresponding to the different sizes. On the bracket 120 is a projection 140 on which is a mark 142 arranged to register with one or another of the size marks 138. 60 Having adjusted the plate 128 relatively to

the wheel 124 in accordance with the style of shoe the operator turns the wheel 124 to bring the mark indicating the size of the shoe upon which the work is to be performed into registration with the fixed mark 142. 70 The corresponding turning movement of the worm 118 adjusts the toe gripper in the manner hereinbefore described for the length of tip on the style and size of shoe in question, and the toe gripper having been thus adjusted the toe end face of the last at the limit of its rearward movement will be located precisely at the required distance from the ends of the tip seam held in predetermined relation to the side gripper jaws. It 80 will be evident that such adjustment is automatically maintained during the time that the machine is to operate upon shoes of the same style and size, and that when a change is to be made in the character of the work 85 the proper readjustment of the toe gripper may be quickly and accurately effected.

It will be understood that following the backward movement of the toe gripper its updraw movement is effected by the operation of the lever 26 in the manner usual in machines of this type, such movement of the gripper being permitted by the sliding connection between the plate 114 and the plugs 112. Near its lower end the plate 90 114 is cut inward on each side, as indicated at 144, and each of the plugs 112 is cut away at its rear side, as indicated at 146. This construction permits the release of the toe gripper from control of the plugs 112 before it completes its updraw movement, such release taking place when the narrower lower portion of the plate arrives in position between the cut back rear portions of the plugs. The toe gripper overdraw springs 95 100 105 110 115 120 125 130 135 140 145 150 155 160 165 170 175 180 185 190 195 200 205 210 215 220 225 230 235 240 245 250 255 260 265 270 275 280 285 290 295 300 hold the roll 166 in operative relation to the cam and serves also, when the cam permits, to operate the link 162 and the crank arm 160 to turn the shaft 158 in a direction to 5 withdraw the bar 148 from the toe gripper bar 25. By reference to Fig. 13 it will be seen that such withdrawal of the bar 148 takes place immediately upon the starting of the machine, thus permitting the toe 10 gripper to be swung backward by its connections to the cam 80 in the manner hereinbefore described.

It will also be seen by reference to Fig. 7 that the bar 148 carries means for determining 15 the spacing of the side grippers, comprising a wedge block 172 provided on its opposite sides with inclined faces in engagement with rolls 174 on pivoted lever arms 176 which carry blocks 178 having 20 bearing contact with the inner faces of the side gripper bars 6. In the present construction the wedge block 172 is adjustable lengthwise of the bar 148 to space the side grippers different distances apart for different 25 sizes of shoes, the block being connected by means of a rack bar 180 to a pinion 182 formed on a sleeve 184 which is normally connected by means of a toothed clutch 186 to the shaft 158. By engaging a hand wheel 30 188 on the end of the sleeve 184 and moving the sleeve endwise against the tension of a spring (not shown) the sleeve may be disconnected from the shaft and then turned to adjust the wedge block relatively to the 35 bar 148. It will be evident that this gripper spreading mechanism comprising the wedge block 172 and the bar 148, in its broad features is similar to mechanism heretofore provided in machines of this general type, 40 as shown in Patent No. 1,029,387. In the construction herein shown, however, the wedge block 172, normally connected as it is through the clutch teeth 186 to the shaft 158, is moved backwardly with the bar 148 45 immediately after the machine is started, and therefore the side grippers are released to the action of their overdraw springs 48 earlier than in prior constructions, thus causing the side grippers to move inwardly 50 as far as permitted by the last or by the tension of the upper during their updraw. In the return of the parts to starting position the shaft 158 is turned by the action of the cam 168 to move the bar 148 and the 55 wedge block forwardly and thus to move the toe gripper yielding forward until the narrow portion of its plate 114 engages the longer front end portions of the plugs 112, thus alining the plate 114 with the slots in 60 the plugs and causing the plate to enter these slots as the toe gripper is then moved downwardly. Simultaneously the side grippers are moved apart by the action of the wedge block 172 and positioned properly 65 for engagement with the next shoe.

It will be understood that in a properly made shoe the tip line extends across the shoe substantially at right angles to the longitudinal median line of the forepart. If it were feasible therefore to present each 70 shoe to the machine with the longitudinal median line of the forepart extending perpendicularly to the rear face of the toe gripper jaw, the proper locations for the side grippers would be such as to position the tip 75 seam marks 58 at the opposite sides equal distances rearwardly from the plane of the toe gripper face. Since, however, in modern lasts the longitudinal median line of the heel part extends at a decided angle to the 80 corresponding line of the forepart, this angle representing what is termed the "swing" of the last, it is not usually feasible to present the work in the above-mentioned relation to the toe gripper, since if this were done the 85 heel part of the last would project laterally too far to permit the heel rest properly to engage and position the shoe. It is contemplated therefore that the work shall be presented to the machine herein shown with the 90 longitudinal median line of the forepart inclined to the rear face of the toe gripper in a manner partially to compensate for the lateral swing of the last, such line of course being inclined toward one side of the machine for a right shoe and toward the other side of the machine for a left shoe. This necessitates that one of the side grippers be positioned nearer than the other to the toe 95 gripper for one of the shoes of a pair and that the positions of the opposite side grippers be reversed when the machine is to operate upon the other shoe of the pair. For this purpose the machine is provided 100 with side gripper adjusting mechanism 105 which, as shown in Fig. 8, comprises some of the characteristic features of similar mechanism illustrated in Patent No. 1,029,387. By reference to Fig. 8, and by further reference to said patent, it will be 110 seen that one of the side grippers is connected to a slideable rack bar 190 engaged by a pinion 192 on a transverse adjusting shaft 194, and that the other gripper is connected to a similar rack bar 196 engaged by a pinion 198 fast on said shaft, the rack bars being connected to the respective side grippers by means which permits the grippers to have 115 their characteristic updraw and overdraw movements. It will be seen that the rack 120 bar 190 extends underneath the pinion 192, while the bar 196 extends over the pinion 198, and therefore that by rotation of the shaft 194 movements are imparted to the respective side grippers lengthwise of the 125 shoe simultaneously in opposite directions. For turning the shaft to adjust the grippers the machine is provided with a handle 200 which by movement in one direction adjusts the grippers for a right shoe and by move- 130

ment in the opposite direction adjusts them for a left shoe.

In order to save time for the operator in making the adjustments of the side grippers, 5 the machine is provided with limiting means which may be adjusted for different styles of shoes and when so adjusted serves to predetermine the different locations of the grippers for the right and left shoes of that 10 style. This mechanism comprises a pin 202 mounted eccentrically at one end of the shaft 194 to turn with the shaft and an adjustable limiting member 204 pivotally mounted on a pin 206 on a bracket 208 and provided with 15 a substantially V-shaped recess or guideway 210 between the opposite walls of which the pin 202 is located. It will be evident by reference to Fig. 9 that the walls of the guideway 210 positively limit turning movement 20 of the shaft 194 in both directions and that as the member 204 is adjusted about its pivot the extent of such possible movement of the shaft is varied, the relation between the pin and the guideway being such that any in- 25 crease or decrease in the range of movement of the shaft in one direction is accompanied by a corresponding increase or decrease of equal extent in the opposite direction. With the member 204 properly adjusted for the 30 style of shoe in question, the side grippers are properly positioned to operate, for example, upon a right shoe of that style when the handle 200 is moved as far in one direction as is permitted by engagement of the 35 pin 200 with one of the walls of the guideway 210, and all that the operator is required to do in order to readjust the side grippers for a left shoe of that style is to move the handle 200 as far in the opposite direction as 40 the limiting means permits. Obviously such adjustments may be very quickly effected without need for any particular care upon the operator's part. Further to facilitate such adjustment and to assist in maintaining 45 the grippers in adjusted position, the handle 200 carries a spring pressed pin 212 the inner end of which is held in engagement with a guide member provided with surfaces 214 which slope in opposite directions from 50 a central high point. The pin 212 may be pulled outwardly if desired by means of a controlling lever 216 to which it is connected. It is contemplated, however, that the tension of the spring pressed pin will be such that 55 the operator may conveniently swing the handle to move the pin past the high point on its guide without the necessity for withdrawing it. It will be evident that the sloping surfaces 214, by wedging engagement 60 with the pin 212, tend to swing the handle in one direction or the other in such manner as to hold the pin 202 against the corresponding wall of its guideway, the construction thus not only permitting precise adjustment of the grippers in the manner deter-

mined by the guideway 210 but also serving to maintain the grippers in adjusted position. By reference to Figs. 8 and 9 it will be seen that the member 204 is provided with an arcuate series of depressions 218 arranged to be engaged by a spring held plug 220 to maintain the limiting member in different positions of adjustment.

In order still further to insure the proper angular relation of the tip line to the last, 75 the machine is provided with means for determining accurately the angular position of the last relatively to the plane of the rear face of the toe gripper, comprising mechanism for determining different limits 80 of lateral displacement of the heel rest 42. It will be recognized that, similarly to the construction shown in Patent No. 1,029,387, the heel rest member 42 comprises oppositely inclined side portions which are arranged 85 partially to embrace the heel end of the shoe and thus to determine the lateral position of said heel end, the member 42 being mounted upon trunnions 222 on the lower ends of arms 224 which are mounted on 90 pivots 230 to swing from side to side, this mechanism being operated as described in detail in said patent to carry the heel rest 95 yielding into supporting and positioning engagement with the shoe and then to hold 100 it in operative position. As the heel rest is moved up into engagement with the shoe, any lateral displacement of the heel end of the shoe in unsymmetrical relation to the member 42 will cause the member to be 105 swung laterally by movement of the arms 224 about the pivots 230 and may also cause the shoe to be swung reversely to some extent, until the shoe is seated centrally between the opposite diverging portions of 110 the member. For the purposes of this invention one of the heel rest socket members mounted on the trunnion 222 is provided with a laterally extending arm 234 upon 115 which is pivotally mounted an adjusting member 236 provided with a V-shaped recess or guideway having opposite walls 238 arranged to coöperate with a pin 240 mounted on the lower end of the adjacent arm 224, this arrangement being similar to the pin 115 and guide arrangement for the side gripper adjusting means. A spring pressed plug 242 on the arm 234 is arranged to engage in different depressions in the face of the member 236, as shown in Fig. 12, to hold 120 the member in different adjusted positions. It will be evident that as the arms 224 are 125 swung laterally in one direction the pin 240 is tipped downwardly until it engages the lower wall of the guideway 238, and that swinging movement of the arms in the opposite direction will cause the pin to engage the opposite wall of the guideway. When the heel rest is in its central position the pin 130 is located equidistantly from the walls of

the guideway, the limiting means thus permitting the rest to be moved equal distances in opposite directions, the extent of such movements being varied in accordance with the adjustment of the member 236. Positive limiting means is thus afforded to insure the correct angular relation of the last to the toe gripper for both the right and left shoes of any given style. All that the operator is required to do in order to cause the heel rest to perform its function properly is to position the shoe in the machine with the heel part deflected laterally in one direction or the other, accordingly as the shoe presented is a right or a left shoe, a greater distance than required for the final position of the shoe, and when the machine is operated the shoe, by its engagement with the heel rest, will swing the rest laterally as far as permitted by the pin 240 and will then itself be swung into its correct location by the wedging action of the rest. While small changes in the "swing" of the last may be compensated for by adjustment of either the side grippers or the heel rest alone, it is contemplated that usually both the member 204 and the member 236 will be adjusted in order to avoid any exaggerated displacement of the grippers or of the heel end of the last. If desired suitable marks may be provided to indicate corresponding positions of the different adjusting members.

The cycle of operations of the machine will be more fully understood by reference to Fig. 13. After the work has been positioned in the manner hereinbefore described, the side grippers closed and the machine started through the operation of the treadle rod 30, the cam 168 first releases the roll 166 and causes the gripper spreading mechanism shown in Fig. 7 to be withdrawn in such manner as to permit rearward movement of the toe gripper. The rise *a* on the cam 80 then immediately becomes effective to swing the toe gripper backwardly, thus pushing the last rearwardly within the upper, this movement of the toe gripper being substantially or approximately completed before the gripper operating means becomes effective to close the toe gripper and to impart updraw movement to the grippers. Following the rearward movement of the last to the point required, the toe and side grippers are operated to pull the upper. At the beginning of the updraw movement of the toe gripper the roll 92 encounters a depression *b* on the face of the cam 80, thus permitting the spring 116 to operate the gripper controlling means in such manner as to swing the toe gripper reversely in a forward direction, causing it to clear the toe end of the last without objectionable engagement with the margin of the sole or insole and also to impart a forward draft to the portion of the upper extending over the

top of the toe of the last. As the toe gripper continues its updraw movement, the wide portion of the plate 114 is pulled out of the slots in the plugs 112 and the gripper is released to the action of its overdraw 70 springs to permit it to swing inward, as suggested in Fig. 4, during the latter portion of its updraw movement. The upper pulling movement of the grippers having been completed, the machine comes to rest 75 at the point indicated by the arrows *c* on Fig. 13.

When the machine is again started the side clamp arms 43 are swung inward against the shoe, and the toe and side over-laying and tacking mechanisms are swung inward and operated in the usual manner, causing the grippers to release the upper, and then driving tacks to fasten the upper 80 at the toe and the sides. At the point *d* 85 (Fig. 13) a rise on the cam 80, arranged to operate during the inward movement of the tacker arms, causes the toe gripper controlling frame 106 to move the plugs 112 rearwardly for a short distance, and at the point *e* 90 a further rise on the cam causes these plugs to be moved still farther rearwardly, this latter movement taking place substantially at the time when the roll 166 encounters the cam 168 whereby the spreading 95 mechanism (Fig. 7) is operated to return the grippers to their starting positions. By the action of this mechanism the toe gripper is moved outwardly to meet the plugs 112 and to align the plate 114 with the slots 100 in the plugs, the plate sliding into these slots as the toe gripper moves downwardly in its return to starting position. The frame 106 having thus been connected again to the toe gripper, the cam 80 at the point *f* 105 causes the frame to be swung forwardly by the spring 116 and thus to carry the toe gripper to its forward limit of movement ready for operation upon the next shoe.

Having thus described the invention, what I claim as new and desire to secure by Letters Patent of the United States is:

1. A machine of the class described having, in combination, grippers for engaging an upper at opposite sides of a last, power means for effecting relative movement of said grippers and the last to pull the upper across the forepart of the last, means for causing said grippers to close on the upper before the machine is started, and means 115 automatically operative after the starting of the machine to effect a relative movement of said grippers and the last in a direction to pull the upper lengthwise from the heel end forwardly.

2. A machine of the class described having, in combination, grippers for engaging an upper at opposite sides of a last, power means for effecting relative movement of said grippers and the last to pull the upper 130

across the forepart of the last, means for causing said grippers to close on the upper before the machine is started, and additional power operated means for effecting a 5 relative movement of said grippers and the last in a direction lengthwise of the last after the grippers have closed and prior to said upper pulling operation.

3. A machine of the class described having, in combination, grippers for engaging an upper at opposite sides of a last, power means for effecting relative movement of said grippers and the last to pull the upper across the forepart of the last, means for 10 starting the power operation of the machine, connections between the starting means and said grippers to cause them to close upon the upper before the machine is started, and means automatically operative 15 after the machine is started to effect a relative movement of said grippers and the last in a direction to pull the upper lengthwise from the heel end forwardly.

4. A machine of the class described having, in combination, grippers for engaging an upper at opposite sides of a last, power means for operating said grippers to pull the upper across the forepart of the last, manual means for causing said grippers to 25 close on the upper before the machine is started, and additional power operated means for effecting a relative movement of said grippers and the last in a direction lengthwise of the last in time relation to 30 said upper pulling operation.

5. A machine of the class described having, in combination, grippers for engaging an upper at opposite sides of a last, power means for effecting relative movement of 40 said grippers and the last to pull the upper across the forepart of the last, manual means for causing said grippers to close on the upper, and power means for effecting a relative movement of said grippers and the 45 last in a direction lengthwise of the last after said grippers have closed and prior to said upper pulling operation.

6. A machine of the class described having, in combination, grippers for engaging an upper at opposite sides of a last, power 50 means for effecting relative movement of said grippers and the last to pull the upper, means for starting the machine, and connections between said starting means and the grippers to cause them to close upon the upper before the machine is started.

7. A machine of the class described having, in combination, side grippers having means for determining a definite location 60 for the tip seam of an upper in the gripper jaws, power operated means for effecting relative movement of said grippers and the last to pull the upper, and means for effecting, after the starting of the power operation 65 of the machine and prior to any sub-

stantial tensioning of the upper, a relative movement of the last and said grippers automatically limited in extent and in a direction lengthwise of the last for locating the tip seam at a predetermined distance 70 from the toe end of the last.

8. A machine of the class described having, in combination, side grippers constructed and arranged for engagement with the margin of an upper in predetermined relation to the tip seam, power means for effecting relative movement of said grippers and the last to pull the upper, means for causing said grippers to close on the upper before the machine is started, and means for effecting a predetermined extent of relative movement of said grippers and the last in a direction lengthwise of the last after the machine is started for locating the tip seam 80 at a definite distance from the toe end of the 85 last.

9. A machine of the class described having, in combination, side grippers having means for determining a definite location for the tip seam of an upper in the gripper jaws, power means for operating said grippers to pull the upper, and means automatically operative in time relation to the upper pulling operation to effect a predetermined relative movement of the last and said grippers in a direction lengthwise of the last prior to the upper pulling movement of the grippers to locate the tip seam at a predetermined distance from the toe end of the 95 last.

10. A machine of the class described having, in combination, grippers for engaging an upper at opposite sides of a last, means for causing said grippers to close on the upper, a sole rest, means for effecting relative movement of said grippers and the sole rest to pull the upper, and means independent of the sole rest for imparting to the last a rearward lengthwise movement automatically limited in extent after said grippers 105 have closed on the upper.

11. A machine of the class described having, in combination, grippers for engaging an upper at opposite sides of a last, means for effecting relative movement of said grippers and the last to pull the upper, and power operated means constructed and arranged to push against the end face of the last and impart to the last a rearward lengthwise movement of predetermined extent while said grippers hold the upper.

12. A machine of the class described having, in combination, grippers for engaging an upper at opposite sides of a last, a sole rest, means for effecting relative movement 115 of said grippers and the sole rest to pull the upper, and means independent of the sole rest and operative in time relation to said relative upper pulling movement of the grippers and the sole rest to move the last 125 130

rearwardly lengthwise of the upper prior to any substantial tensioning of the upper over the forepart of the last.

13. A machine of the class described having, in combination, grippers for engaging an upper at opposite sides of a last, power means for effecting relative movement of said grippers and the last to pull the upper, means for causing said grippers to close upon the upper before the machine is started, and means automatically operative after the machine is started to force the last rearwardly lengthwise of the upper.

14. A machine of the class described having, in combination, grippers for engaging an upper at opposite sides of a last, means for effecting relative movement of said grippers and the last to pull the upper, and means automatically operative to impart to the last a rearward lengthwise movement relatively to said grippers after said grippers have closed on the upper and prior to any substantial tensioning of the upper across the forepart of the last.

25 15. A machine of the class described having, in combination, grippers for engaging an upper at opposite sides of a last, power means for operating said grippers to pull the upper, and means for imparting to the last a rearward lengthwise movement of predetermined extent prior to said upper pulling movement of the grippers.

16. A machine of the class described having, in combination, grippers for engaging an upper at opposite sides of a last, power means for operating said grippers to pull the upper, means for causing said grippers to close upon the upper before the machine is started, and means automatically operative after the machine is started and prior to the upper pulling movement of said grippers to force the last rearwardly lengthwise of the upper.

17. A machine of the class described having, in combination, side grippers constructed and arranged for engagement with an upper in predetermined relation to the tip seam, and power means for engaging the end face of the last and imparting to the last a rearward lengthwise movement relatively to said grippers after they have closed on the upper and while the upper is substantially free from lateral tension to locate the tip seam at a predetermined distance from the toe end of the last.

18. A machine of the class described having, in combination, grippers for engaging an upper at opposite sides of a last, power means for engaging the end face of the last and imparting to the last a lengthwise movement relatively to said grippers after they have closed on the upper, and means adjustable to vary the limit of said movement of the last.

19. A machine of the class described having, in combination, grippers for engaging an upper at the toe end and at opposite sides of a last, and means for moving the toe gripper rearwardly in engagement with the end face of the last to force the last rearwardly within the upper.

20. A machine of the class described having, in combination, grippers for engaging an upper at the toe end and at opposite sides of a last, and power means for imparting to the toe gripper, in engagement with the end face of the last, a rearward movement of predetermined extent while the side grippers hold the upper to force the last rearwardly within the upper.

21. A machine of the class described having, in combination, grippers for engaging an upper at the toe end and at opposite sides of the last, means for causing the side grippers to close upon the upper before the toe gripper closes, and means for moving the toe gripper rearwardly in engagement with the end face of the last after the side grippers have closed to force the last rearwardly within the upper.

22. A machine of the class described having, in combination, grippers for engaging an upper at the toe end and at opposite sides of a last, power means for effecting relative movement of said grippers and the last to pull the upper, means for causing the side grippers to close before the toe gripper closes, and means for moving the toe gripper rearwardly prior to said upper pulling operation to force the last rearwardly within the upper and for then closing the toe gripper and effecting said upper pulling operation.

23. A machine of the class described having, in combination, grippers for engaging an upper at the toe end and at opposite sides of the last, power means for effecting relative movement of said grippers and the last to pull the upper, means for causing the side grippers to close upon the upper prior to the toe gripper and before the machine is started, and means automatically operative after the machine is started for moving the toe gripper rearwardly to force the last backwardly into the upper and for then closing the toe gripper and effecting said upper pulling operation.

24. A machine of the class described having in combination, grippers for engaging an upper at the toe end and at opposite sides of a last, power means for effecting relative movement of said grippers and the last to pull the upper, means for starting the power operation of the machine, connections between said starting means and the side grippers to cause them to close on the upper before the machine is started, and means automatically operative after the machine is

- started for moving the toe gripper rearwardly to force the last backwardly within the upper.
25. A machine of the class described having, in combination, grippers for engaging an upper at the toe end and at opposite sides of a last, means for effecting relative movement of said grippers and the last to pull the upper, means for causing the side grippers to close before the toe gripper closes, and means for moving the toe gripper in a rearward direction before it closes to force the last backwardly within the upper. 70
- 10 26. A machine of the class described having, in combination, side grippers arranged to engage an upper in predetermined relation to the tip seam, a toe gripper arranged to permit the end face of the last to be positioned against it, and means for moving 75 said toe gripper rearwardly a predetermined distance in engagement with the end face of the last to determine the length of the tip. 80
- 15 27. A machine of the class described having, in combination, side grippers arranged to engage an upper in predetermined relation to the tip seam, a toe gripper arranged to permit the end face of the last to be positioned against it, power means for effecting 85 relative movement of said grippers and the last to pull the upper, and means for imparting to the toe gripper in engagement with the end face of the last a rearward movement automatically limited in extent to determine the length of the tip. 90
- 20 28. A machine of the class described having, in combination, grippers for engaging an upper at the toe end and at opposite sides of a last, means for effecting relative movement of said grippers and the last to pull the upper, means for imparting to the toe gripper a rearward movement automatically limited in extent to force the last backwardly within the upper, and means adjustable to vary the limit of rearward movement of the toe gripper. 95
- 25 29. A machine of the class described having, in combination, grippers for engaging an upper at the toe end and at opposite sides of a last, means for effecting relative movement of said grippers and the last to pull the upper, means for imparting to the toe gripper a rearward movement automatically limited in extent to force the last backwardly within the upper, and means for adjusting the rearward limit of movement of the toe gripper, said adjusting means comprising parts arranged to be moved first relatively and then together to determine the correct adjustment with reference to 100 both the style and the size of the shoe. 105
- 30 30. A machine of the class described having, in combination, grippers for engaging an upper at the toe end and at opposite sides of a last, power means for effecting relative movement of the grippers and the last to 110
- 35 pull the upper, and additional power operated means for imparting to the toe gripper a positive rearward movement in engagement with the end face of the last. 115
- 40 31. A machine of the class described having, in combination, grippers for engaging an upper at the toe end and at opposite sides of a last, a power shaft, connections between said shaft and the grippers for operating them to pull the upper, overlaying and fastening devices arranged to be operated by said power shaft, and additional connections between said shaft and the toe gripper for moving it rearwardly lengthwise of the last independently of the overlaying and fastening devices. 120
- 45 32. A machine of the class described having, in combination, grippers for engaging an upper at the toe end and at opposite sides of a last, a power shaft, connections between said shaft and the grippers for operating them to pull the upper, and additional connections between said shaft and the toe gripper constructed and arranged to move said gripper rearwardly in engagement with the end face of the last prior to its upper pulling movement to force the last backwardly within the upper. 125
- 50 33. A machine of the class described having, in combination, side grippers arranged to engage an upper in predetermined relation to the tip seam, a toe gripper arranged to permit the end face of the last to be positioned against it, and controlling means for said toe gripper arranged to position it initially farther forward than required for the correct length of the tip and to move it rearwardly in engagement with the end face of the last the distance required to determine the correct tip length. 130
- 55 34. A machine of the class described having, in combination, grippers for engaging an upper at the toe end and at opposite sides of a last, means for effecting relative movement of said grippers and the last to pull the upper, and means for moving the toe gripper rearwardly in engagement with the end face of the last and then forwardly in time relation to said upper pulling operation. 135
- 60 35. A machine of the class described having, in combination, grippers for engaging an upper at the toe end and at opposite sides of a last, means for operating said grippers to pull the upper, and means for moving the toe gripper rearwardly in engagement with the end face of the last before it is operated to pull the upper and then forwardly to permit it to clear the end face of the last. 140
- 65 36. A machine of the class described having, in combination, grippers for engaging an upper at the toe end and at opposite sides of a last, means for operating said grippers to pull the upper, controlling means constructed to guide the toe gripper in its upper pulling movement, and means for operating 145

said controlling means to impart to the toe gripper a rearward movement lengthwise of the last in time relation to its upper pulling movement.

5 37. A machine of the class described having, in combination, grippers for engaging an upper at the toe end and at opposite sides of a last, means for operating said grippers to pull the upper, controlling means 10 constructed to impart to the toe gripper a movement lengthwise of the last, said controlling means being also constructed to guide the toe gripper in the initial portion of its upper pulling movement and then to release it, and means for returning the toe gripper subsequently into operative relation to said controlling means.

15 38. A machine of the class described having, in combination a toe gripper, means for 20 operating said gripper to pull the upper, controlling means for imparting to the toe gripper in time relation to its upper pulling movement a rearward movement and then a forward movement, said controlling 25 means being constructed to guide the gripper in its upper pulling movement and then to release it, means for causing said gripper to overdraw the upper when it is thus released, and means for subsequently 30 returning said gripper into operative relation to said controlling means.

35 39. A machine of the class described having, in combination, a toe gripper, means for 40 operating said gripper to pull the upper, and additional power operated means having a rigid connection with said gripper for imparting to said gripper positively a rearward movement of determinate extent.

45 40. A machine of the class described having, in combination, a toe gripper, means for 45 operating said gripper to pull the upper, an oscillatory member having a link connection with said gripper for moving it rearwardly, and means for imparting operative movement to said member.

50 41. A machine of the class described having, in combination, a toe gripper, means for operating the gripper to pull the upper, an oscillatory member connected to said gripper for moving it rearwardly, and means for imparting operative movement to said member including connections constructed and arranged for varying the limit of movement of the gripper under the control of said 55 member.

55 42. A machine of the class described having, in combination, a toe gripper, means for imparting updraw movement to said gripper, an oscillatory device in front of said gripper having means for guiding the gripper in its updraw movement, and means for operating said device to move the gripper lengthwise of the last.

60 43. A machine of the class described having, in combination, a toe gripper, means for 65

operating said gripper to pull the upper, means for imparting to said gripper an overdraw movement, and guiding means constructed and arranged to release said gripper to the action of said overdrawing means before its upper pulling movement is completed.

70 44. A machine of the class described having, in combination, a toe gripper, means for operating said gripper to pull the upper, means for imparting an overdraw movement to said gripper, guiding means constructed and arranged to restrain said gripper initially from overdrawing movement and then to release it to permit said movement, and means for subsequently returning said gripper into operative relation to said guiding means.

75 45. A machine of the class described having, in combination, upper gripping means, 80 mechanism for operating said upper gripping means to pull and to overdraw the upper and then to hold the upper in overdrawn position with the machine at rest, and means operative after the machine is 85 again started to fasten the upper in overdrawn position.

85 46. A machine of the class described having, in combination, a gripper for engaging 90 an upper on a last, means for effecting relative movement of said gripper and the last to pull the upper, means for moving said gripper inwardly to overdraw the upper, and controlling means constructed and arranged to determine the initial position of 95 said gripper and movable to permit the overdrawing movement of the gripper before its upper pulling movement is completed.

95 47. A machine of the class described having, in combination, a gripper for engaging 100 an upper on a last, means for imparting an updraw movement to said gripper, means for moving said gripper inwardly to overdraw the upper, and controlling means constructed to guide the gripper in its updraw 105 movement and to release it to permit the overdraw to be effected before said updraw movement is completed.

110 48. A machine of the class described having, in combination, grippers for engaging 115 an upper at the toe end and at opposite sides of a last, means for effecting relative movement of said grippers and the last to pull the upper, means for operating said grippers to overdraw the upper, gripper spreading mechanism constructed and arranged to determine the initial positions of said grippers, and means for operating said spreading mechanism to cause the overdrawing operation to be effected before said upper pulling 120 operation is completed.

125 49. In a machine of the class described, an upper engaging gripper, power means for operating said gripper to pull the upper, means for starting the machine, and connec- 130

tions between said starting means and the gripper to cause it to close on the upper before the machine is started.

50. A machine of the class described having, in combination, grippers for engaging an upper at opposite sides of a last, means for determining relative positions of said grippers lengthwise of the last corresponding to the required angle of the tip line of 5 the upper, a heel rest movable laterally in response to pressure of the work, and means for determining a lateral limit of movement of said heel rest corresponding to the relative arrangement of said grippers to insure 10 the correct relation of the tip line to the longitudinal median line of the shoe.

51. A machine of the class described having, in combination, grippers for engaging an upper at opposite sides of a last, means 20 for determining relative positions of said grippers lengthwise of the last corresponding to the required angle of the tip line of the upper, a heel rest, and means for determining a lateral position of said heel rest 25 corresponding to the relative arrangement of said grippers to insure the correct relation of the tip line to the longitudinal median line of the shoe.

52. A machine of the class described having, in combination, grippers for engaging an upper at opposite sides of a last in predetermined relation to the tip seam, adjusting means constructed and arranged to position said grippers relatively lengthwise of 30 the last in accordance with the required angle of the tip line, said adjusting means being movable to reverse the positions of the grippers for right and left shoes, a heel rest laterally movable in opposite directions 35 in response to pressure of the work, and means for determining limits of movement of said heel rest corresponding to the adjusted relations of the grippers to insure the correct angular relation of the tip lines to 40 the longitudinal median lines of the right and left shoes.

53. A machine of the class described having, in combination, upper gripping means including grippers for engaging an upper 50 at opposite sides of a last in predetermined relation to the tip seam, a heel rest, means for determining a relative adjustment of said grippers lengthwise of the last and a lateral position of said heel rest such as to 55 cause the tip line of the upper to be disposed in the correct angular relation to the longitudinal median line of the last, means for effecting a relative movement of the grippers and the last in a direction lengthwise of 60 the last to position the tip line at the correct distance from the end of the last, and means for effecting relative movement of said last and upper gripping means to pull the upper.

65. 54. A machine of the class described hav-

ing, in combination, grippers for engaging an upper at the toe end and at opposite sides of a last, the side grippers being arranged to engage the upper in predetermined relation to the tip seam, a heel rest, means for determining a relative adjustment of the side grippers lengthwise of the last and a lateral position of said heel rest such as to cause the tip line of the upper to be disposed in the correct angular relation to the longitudinal median line of the last, means for imparting to said toe gripper a rearward movement in engagement with the end face of the last to force the last backwardly a predetermined distance to give the correct 75 length of tip, and means for effecting relative movement of said grippers and the last to pull the upper.

55. In a machine of the class described, the combination with grippers for engaging 80 an upper at opposite sides of a last, of means movable to effect a relative adjustment of said grippers lengthwise of the last, and means for limiting automatically the movement of said adjusting means to cause 85 said grippers to be relatively positioned in accordance with the required angle of the tip line of the upper.

56. In a machine of the class described, the combination with grippers for engaging 90 an upper at opposite sides of a last, of means movable in opposite directions to effect relative adjustments of said grippers for right and left shoes, and means for limiting automatically the opposite movements of said 95 adjusting means to cause the grippers to be positioned correctly in accordance with the required angles of the tip lines of the respective shoes.

57. In a machine of the class described, the combination with grippers for engaging 100 an upper at opposite sides of a last, of means for effecting a relative adjustment of said grippers lengthwise of the last, and means for limiting automatically the movement of said adjusting means, said last-named means being movable to vary the limit of said adjusting movement.

58. In a machine of the class described, the combination with grippers for engaging 105 an upper at opposite sides of a last, of means movable in opposite directions to effect relative adjustments of said grippers for right and left shoes, and means for limiting automatically said opposite movements of the 110 adjusting means, said limiting means being movable to effect equal variations in the range of said opposite movements.

59. In a machine of the class described, the combination with grippers for engaging 115 an upper at opposite sides of a last, of means comprising a rotatable member for effecting relative adjustments of said grippers lengthwise of the last, a pin eccentrically mounted on said member, and a stop member having 120

a substantially V-shaped recess the walls of which are arranged for engagement with said pin to limit the opposite movements of said adjusting means, said stop member being adjustable to vary said limits of movement.

60. In a machine of the class described, the combination with grippers for engaging an upper at opposite sides of a last, of means 10 movable to effect relative adjustment of said grippers lengthwise of the last, means for limiting the movement of said adjusting means, and yieldable wedge mechanism arranged to hold said adjusting 15 means yieldingly at said limit of movement.

61. In a machine of the class described, the combination with grippers for engaging an upper at opposite sides of a last, of means 20 movable in opposite directions to effect relative adjustments of said grippers lengthwise of the last for right and left shoes, means for limiting the opposite movements of said adjusting means, and wedge mechanism arranged to hold said adjusting means 25 yieldingly at either of its limits of movement while permitting it to be moved to reverse the positions of the grippers.

62. In a machine of the class described, the combination with grippers for engaging 30 an upper at opposite sides of a last, of means movable in opposite directions to effect relative adjustments of said grippers lengthwise of the last for right and left shoes, means for limiting the opposite movements of said adjusting means, manual 35 means for effecting said movements, and means comprising a guide having oppositely sloping surfaces and a spring held pin in engagement with said surfaces to cause said 40 adjusting means to be held yieldingly at either of its limits of movement.

63. In a machine of the class described, a heel rest mounted for lateral movement in response to pressure of the heel end portion 45 of a shoe, and means for limiting automatically said lateral movement of the heel rest, said limiting means being adjustable to determine different limits of movement of the rest.

64. In a machine of the class described, a 50 heel rest mounted for lateral movements in opposite directions respectively in response to pressure of the heel end portions of right and left shoes, and limiting means constructed and arranged to determine automatically 55 equal ranges of movement of said rest in opposite directions.

65. In a machine of the class described, a heel rest mounted for lateral movements in 60 opposite directions respectively in response to pressure of the heel end portions of right and left shoes, and means for limiting the opposite movements of said rest, said limiting means being adjustable to effect equal 65 variations in the range of said opposite movements.

66. In a machine of the class described, a heel rest mounted for movements in opposite directions in response to pressure of the work, and means for limiting the opposite 70 movements of said rest, said limiting means comprising a pin and an adjustable stop member having a substantially V-shaped recess the opposite walls of which are arranged to engage said pin to limit the movements of the rest.

67. In a machine of the class described, a gripper for engaging an upper on a last, power operated means for effecting relative movement of said gripper and the last to 80 pull the upper, means for starting the power operation of the machine, and mechanism operated by said starting means for causing said gripper to close on the upper before the machine is started.

68. In a machine of the class described, a gripper for engaging an upper on a last, a gripper lever, power means for operating said lever to impart to the gripper an upper pulling movement, a manually operated 90 member for starting the power operation of the machine, and mechanism operated by said member for imparting to said gripper lever a movement in the direction of pull before the machine is started.

In testimony whereof I have signed my name to this specification.

WILLIAM C. STEWART.
